HOSE ATTACHING DEVICE

Vita Buchanan, New York, N. Y.

Application May 21, 1932, Serial No. 612,718

9 Claims. (Cl. 24—73)

My invention relates to improvements in hose supporting means in corsets, and the same has for its object to provide an attaching device or member which may be readily secured to holding members depending from the corset, and when attached will readily accommodate itself to the changing positions of the wearer.

Further, said invention has for its object to provide an attaching device which may be slidably disposed upon a holding member or elastic, and which will be maintained at substantially right angles to the strain of the holding member upon which the attaching device is disposed.

Further, said invention has for its object to provide an attaching device in which the holding member or elastic will be held flat against the legs of the wearer, and not interfere with the free movement thereof.

Other objects will in part be obvious, and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawing—

Figure 1 is a side view of a corset showing one form of holding and attaching means for the opposite sides thereof constructed according to and embodying my said invention;

Figs. 2 and 3 are face views of right and left hand attaching devices, and

Fig. 4 is a detail face view showing one of the hook members secured at the lower edge of the corset, and a portion of one holding member with a combined adjusting member and eye which is adapted to engage with said hook member.

In said drawing 10 designates a corset which may in general be of any desired type, but which, for the purpose of illustrating my present invention, is shown as formed of one piece, being provided at the opposing front edges with the usual hooks and eyes for securing the same together. The said body portion may be made entirely of elastic or of substantially inelastic material, or the same may be made partly of both of said materials, i. e., partly of elastic and partly inelastic material and provided at different points with elastic inserts or gores.

The body portion of the corset is preferably made of inelastic material, and is provided at its sides with vertical casings 12, and at its back and front with casings 13. The casings are adapted to receive the usual stays. It will, of course, be

obvious that any number of casings may be employed.

The lower rear portion of the corset body which constitutes essentially the seat portion of the garment, is cut away to receive an elastic insert 5 15 whose inner edges are secured by sewing to the cut away portions of said body.

The lower edge of the seat portion 15 extends slightly below the lower rear edge of the corset and terminates in two diagonal, oppositely extending straps 17, 17^a, to the ends of which are secured the inner ends of holding members 18, 18^a, respectively, which may be made of any suitable material, but preferably of elastic webbing. The outer or free end of each of said holding 15 members 18, 18^a, is passed through the horizontal slots 19, 19^a, and over rollers 19^a of the attaching devices 19 hereinafter described, and then adjustably secured to an eye member 20 by passing the same in succession through the 20 slots 21, 22, 23, and then folded over and again passed through the slot 21. By this arrangement the lengthening or shortening of each holding member, in accordance with the requirements of the wearer, may be readily accomplished. 25

Each eye member 20 has its top bar arranged at an angle to the intermediate and lower bars so as to form a tapering recess 23, and shaped to facilitate the engagement of said top bar with its respective hook member 24. 30

The hook members 24 are secured to the lower edge of the corset; one adjacent to each meeting edge of the garment, and one at each side of the corset. The said hook members may be secured to the garment in any suitable or convenient 35 manner, as by sewing, but preferably by riveting, and for this purpose a bar 26 is provided having a tubular member or eyelet 27 at each end adapted to extend through the fabric of the garment and be received by and clamped over eyes 28 provided at the opposite ends of the hook members 24. 40

The attaching devices or members 19 are arranged at the inner and outer sides of each leg, and each of said devices has a depending vertical 45 loop 29 which, in combination with a button 30, is adapted to engage with the upper edge of the stocking. Each attaching device 19 is further provided at its upper portion with a lower transverse bar 31, and an intermediate transverse bar 50 32, which are arranged parallel to each other to form the slot 19^a therebetween and substantially at right angles to the vertical axis of said loop 29, the latter being of reduced width and depending from the bar 31 at a location closer to one 55

end thereof than to the other end. Above the intermediate bar 32 is a top bar 33 which is arranged at an angle to said intermediate bar 32, and extends beyond the same at one end thereof. 5 The bars 32 and 33 form therebetween the tapered slot 19' staggered or offset laterally relative to the slot 19² with the wider portion thereof projecting beyond the slot 19² at the end thereof adjacent the depending portion 29. The bars 31, 10 32, 33 are united at their ends by rounded portions 34 forming opposite sides of unequal length extending at an inclination relative to the vertical axis of the device. The several parts are shaped and disposed at suitable angles corresponding to 15 the directions of the several strains to which the device is subjected in use, and to prevent undue wear upon the holding members 18, 18^a the transverse members 32 is provided with an antifriction roller 19^a. A small transverse slot 35 is provided 20 to receive a strap 36, the lower end of which may carry the button 30.

Both the attaching members 19, and the eye members 20 are made in pairs, i. e., left and right, which are alike in construction, except that the 25 same are reversed.

The operation of the device will be largely obvious from the foregoing description in connection with the drawing. It need merely be noted that by reason of the sliding connection between 30 the attaching devices 19, and the holding members 18, 18^a, the elastic seat of the garment will be held duly under tension and conformed to the buttocks of the wearer at all times, and in all positions the wearer may assume.

It is to be noted that due to the novel construction of the attaching device 19, the holding members 18, 18^a, where the same pass through the 35 said holding device 19, will be held flat against the legs of the wearer without interfering with the free movement of said holding members relative 40 to said attaching devices 19.

This application is a division of my copending application, Serial No. 133,670, filed September 4, 1926, which has resulted in Patent No. 1,859,550, 45 dated May 24, 1932.

Having thus described my said invention, what I claim and desire to secure by Letters Patent is:

1. An attaching device comprising a part including a plurality of transverse portions spaced from each other to provide slots therebetween, a part depending from said first named part and adapted for engagement with a stocking; the upper and intermediate portions of said first named part being disposed angularly relative to each other, and a roller upon said intermediate portion.

2. A device of the character described comprising a part having two substantially parallel slots extending transversely thereof and staggered relative to each other; one of said slots being tapered and having its wider end extending beyond the corresponding end of the other of said slots, and stocking engaging means depending from the slotted part.

3. A device of the character described comprising a part having two substantially parallel slots extending transversely thereof; one of said slots being tapered and having its wider end extending beyond the corresponding end of the other of said slots, and a stocking engaging member depending from the part aforesaid.

4. A device of the character described comprising a part including a plurality of transverse portions spaced relative to each other to provide slots therebetween; one of said slots being tapered from one end towards the other with its wider end extending beyond the corresponding end of the other of said slots, and a stocking engaging member depending from the slotted part.

5. A device of the character described comprising a part having upper and lower transverse slots therein staggered relative to each other, and a stocking engaging part depending from the slotted part in closer relation to the end of the lower slot overlapped by the upper slot than to the opposite end of said lower slot.

6. A device of the character described comprising a part having upper and lower transverse slots therein, the upper slot being tapered and having the wider end thereof extending beyond the corresponding end of the lower slot, and a stocking engaging part depending from the slotted part in closer relation to said corresponding end of the lower slot than to the opposite end thereof.

7. A device of the character described comprising a part including opposite side portions of unequal length arranged substantially parallel to each other and at an angle to the vertical axis 35 of the device, and a plurality of transverse portions spaced from each other, the upper and intermediate transverse portions being disposed angularly relative to each other, and said side and transverse portions forming upper and lower slots 40 staggered relative to each other, the upper slot being tapered and having the wider end thereof extending beyond the corresponding end of the lower slot, and a stocking engaging part of reduced width depending from said first named part in closer relation to the longer side thereof than to the shorter side.

8. An attaching device comprising a part having a plurality of transverse slots therein, the upper slot increasing in width towards one end and having the wider end thereof extending beyond the corresponding end of the lower slot, and a part depending from said first-named part and adapted for engagement with a stocking.

9. A device of the character described comprising a part having a plurality of transverse strap-receiving slots therein, said slots having their adjacent ends overlapping relative to each other, and a stocking engaging portion of reduced width depending from said first-named part with its vertical axis coinciding with the median line of the device.

VITA BUCHANAN.
